WARREN R. LARTER, OF SOUTH ORANGE, NEW JERSEY

COLLAR CLASP

Application filed April 14, 1932. Serial No. 605,234.

This invention relates in general to clasps, and more particularly to clasps for holding the ends of a soft collar in proper position with relation to a necktie.

5 One object of the invention is to provide such a clasp which shall be small, light in weight, and comprise a minimum of metal, and yet be strong and durable so as to firmly grip the ends of a collar to hold them in proper position and prevent loss or displacement of the clasp.

Further objects are to provide such a clasp comprising a main bar and a spring clamping bar secured thereto, and embodying 15 novel and improved features of construction whereby the main bar may be made of considerable size or bulk for ease in handling with a minimum of material, and the clamping bar may be made of light spring metal; 20 and thus to provide such a clasp wherein the main bar is formed of sheet metal and the central portion of the clamping bar is parallel to and in contact with the main bar for substantial parts of the lengths of said bars,

25 the main bar having longitudinal edge portions intermediate its ends bent inwardly tightly over said central portion of the clamping bar throughout the length of said central portion to secure the latter on the 30 main bar, whereby the central portions of the main bar and the clamping bar mutually reinforce each other to provide adequate rigidity of the main bar and sufficient clamping resiliency of the clamping bar.

35 Other objects are to provide a clasp of this character wherein the end portions of the main bar are curved toward the ends of the clamping bar and the central portions of the two bars are curved reversely to the 40 ends of the main bar to further reinforce the clasp and provide a clearance for the knot of a necktie; to provide a soft collar clasp comprising a hollow main bar which shall be light in weight, and a spring clamping

45 bar having its central portions secured within said main bar, the main bar having openings in one wall through which project the end portions of the clamping bar, and the extremities of the clamping bar being disposed in opposed clamping relation to the 50

end portions of the main bar; to provide such a clasp which shall be simple and inexpensive, strong and durable; and to obtain other advantages and results as will be brought out by the following description. 55

Referring to the accompanying drawing, in which corresponding and like parts are designated throughout the several views by the same reference characters,

Figure 1 is a perspective view of a soft 60 collar clasp embodying my invention, showing it applied to a collar;

Figure 2 is a longitudinal horizontal sectional view through the clasp;

Figure 3 is a view similar to Figure 2, 65 showing the clasp in use;

Figure 4 is a longitudinal vertical sectional view, on the line 4—4 of Figure 2;

Figure 5 is a perspective view of one end 70 of the main bar, showing the same in course of manufacture, and

Figure 6 is a similar view, showing the main bar completed and the clamping bar secured thereto.

Specifically describing the illustrated embodiment of the invention, the clasp includes a main bar A and a spring clamping bar B secured to the back thereof. The main bar A is preferably hollow and thin-walled so that it has considerable bulk for ease in handling 80 with a minimum of material and weight.

The spring clamping bar B has a central portion 1 which is fixedly secured within the main bar A, and end portions 2 which project outwardly through openings 3 in the 85 wall of the main bar in offset relation to the central portion 1 and in opposed clamping relation to the end portions 4 of the main bar. Preferably the end portions 2 of the clamping bar are sinuous or curved and their extremities 5 are deflected away from the ends 4 of the main bar to facilitate the insertion of the edges C of a collar or the like between the ends of the clamping bar and the main bar.

90 Preferably the main bar A is formed of sheet metal bent to form a front wall 6, side walls 7, end walls 8 and a back wall 9. The edges of the sheet are disposed in abutting relation on the back of the main bar, as indicated at 10. The central portion 1 of the 100

clamping bar B is parallel to and in contact with the central portion of the main bar for approximately a third part of the lengths of said bars, as clearly shown in Figure 2, and 5 the edge portions of the main bar intermediate their ends are bent inwardly and tightly over the central portion 1 of the clamping bar to secure the clamping bar on the main bar; and said edge portions of the 10 sheet of which the main bar is formed have notches 11 which form openings through which project the end portions 2 of the clamping bar. The back and front walls of the main bar diverge outwardly from each 15 other from the ends of the central portion of the clamping bar. If desired, the abutting edge portions of the sheet of which the main bar is formed, may be soldered to provide a neat appearance.

20 With this construction, it will be observed that the central portions of the main bar and the clamping bar effectually reenforce each other where the greatest strains are imposed upon the clasp. In other words, in the application and removal of the clasp to and from a collar, the strains on the clasp tend to bend it at its middle portion, and these strains are resisted by the combined action of the clamping bar and the main bar.

25 Preferably the ends of the main bar are curved toward the ends of the clamping bar, and the central portions of the two bars are curved in their own planes, as indicated at 12, toward the back of the clasp and re- 30 versely to the curvature of the ends of the main bar. This reverse curvature of the bars further increases the rigidity of the clasp, and also provides a clearance for the knot D of a necktie, as clearly shown in Figure 3 of 35 the drawing.

40 The use of the device will be clear from the foregoing, the ends C of a collar to be held by the clasp being inserted between the extremities of the clamping bar and the end portions of the main bar, the end portions of the clamping bar being sprung away from the main bar, as shown in Figure 3. The resiliency of the clamping bar will effectually hold the ends of the collar in proper position and also prevent displacement of the clasp from the collar. The hollow thin-walled construction of the main bar and the light clamping bar make the clasp extremely light in weight, and at the same time the 45 manner of connecting the clamping bar to the main bar, and the particular formation of the main bar provide adequate rigidity in the end portion of the clasp. The clamping bar is securely held to the main bar close to 50 the extremities of the clamping bar and the end portions 2 are offset at the ends of the central portion 1 away from the main bar and are then returned toward and into opposed clamping relation to the ends of the 55 main bar, so that great strength and re-

siliency in the clamping extremities of the clamping bar are provided with a minimum of metal in the bar.

While I have shown and described the invention as embodied in certain details of construction, it should be understood that this is primarily for the purpose of illustrating the principles of the invention, and that many modifications and changes may be made in the details of construction without departing from the spirit or scope of the invention.

Having thus described the invention, what I claim is:

1. A soft collar clasp, comprising a main bar formed of sheet metal and a spring 80 clamping bar on the back thereof having a central portion parallel to and in contact with said main bar for approximately one-third of the length of said bars, said main bar having longitudinal edge portions intermediate its ends bent inwardly tightly over said central portion of said clamping bar throughout the length of said central portion to secure the latter on said main bar, the central portions of the main bar and the clamping bar being curved in their own planes toward the back of the clasp and the end portions of said clamping bar being offset at the ends of said central portion in a direction 85 away from the main bar opposite to the curvature of said central portion and then returned toward and into opposed clamping relation to the ends of the main bar, whereby the central portions of said main bar and said clamping bar mutually reenforce each other, said longitudinal edge portions are reenforced against bending outwardly and the end portions of said clamping bar have a maximum of resiliency and strength with a 90 small amount of material.

2. A soft collar clasp, comprising a main bar formed of a sheet of metal bent to provide a front wall, side walls, a back wall and end walls, the edges of the sheet meeting in said back wall, and a spring clamping bar 110 in contact with the back of the front wall of said main bar, the longitudinal edge portions of the sheet intermediate their ends overlying the central portion of said clamping bar to secure the clamping bar on the main bar and having notches forming openings through which project the end portions of the clamping bar, the rear wall and front wall of the main bar being in divergent spaced relation to each other outwardly from the ends of said 115 central portion of the clamping bar and the extremities of said clamping bar being arranged in opposed clamping relation to the end portions of the main bar, whereby the central portions of said main bar and said clamping bar mutually reenforce each other and the end portions of the main bar are substantially rigid.
